UNITED STATES PATENT OFFICE.

FREDERICK H. GIBBS, OF NEW YORK, N. Y., ASSIGNOR TO AMERICAN CAR AND FOUNDRY COMPANY, OF ST. LOUIS, MISSOURI, A CORPORATION OF NEW JERSEY.

CAR CONSTRUCTION.

1,170,527.

Specification of Letters Patent.

Patented Feb. 8, 1916.

Application filed November 12, 1912. Serial No. 731,031.

To all whom it may concern:

Be it known that I, FREDERICK H. GIBBS, residing at New York city, New York, and being a citizen of the United States, have 5 invented certain new and useful Improvements in Car Construction, of which the following is a full, clear, and exact description, such as will enable others skilled in the art to which it appertains to make 10 and to use the same, reference being had to the accompanying drawings, which illustrate the preferred form of the invention, though it is to be understood that the invention is not limited to the exact details of 15 construction shown and described, as it is obvious that various modifications thereof will occur to persons skilled in the art.

In said drawings: Figure 1 is a fragmentary transverse sectional view taken through 20 the lower portion of a side wall and adjacent floor of a car constructed to disclose a physical embodiment of my invention and also showing supporting bolster and side 25 posts of conventional design. Fig. 2 is a view similar to Fig. 1, showing a slightly modified form of construction. Fig. 3 is another modified form, showing a door operating shaft beneath the shedding portion. Figs. 4, 5 and 6 are similar views showing 30 slightly different and modified forms. Fig. 7 is a reduced plan view looking down upon a section of the car constructed in accordance with my invention.

This invention relates to side wall constructions for dumping cars, and comprehends in its adaptations the simplification 35 of assemblages, the bracing of the shedding portion of the side wall and the utilization 40 of the space beneath the shedding portion for some of the operative mechanisms controlling the doors and other devices.

A further object of the invention is to provide a substantial holding means for bracing the lower end of the side plate from 45 the underframe, or other substantial part of the car.

Referring to the parts: F is a body bolster or other cross-bearer, H is a side wall of the car bent inwardly at its lower portion and 50 terminating above the body bolster or cross-bearer F.

G is a relatively Z-shaped connecting plate or casting uniting the body bolster or

cross-bearer F with the lower edge of the inclined portion of the side wall. 55

Heretofore attempts have been made to provide a shedding surface for use in gondola cars in which the plate metal forming the side wall was bent inwardly, then bent outwardly parallel with the top edge of the 60 cross-bearer and downwardly at the outer end of the bolster or cross-bearer, the bottom portions of the side wall being respectively horizontal and vertical, and being used as connecting means for the bolsters 65 and intermediate cross-bearers of the car underframe. This type of construction has numerous disadvantages, among which may be noted that the entire side sheet must be manipulated to provide the V-shaped bottom portion, as well as the vertical flange. 70 There are additional disadvantages owing to the weight and size of large sized sheets now used to form the side walls of gondola cars. 75

As a further disadvantage it is noted that in those constructions in which the horizontal and vertical flange portions are integral with the side walls it is frequently necessary to use supplemental braces, due 80 to the thinness of the metal forming the side sheets.

To overcome the above outlined difficulties, the present invention is produced, in which the member indicated by the letter G 85 is preferably formed of pressed sheet metal, or may be made in the form of a casting. When made of pressed sheet metal, it is usually constructed of metal stronger and thicker than the side sheets H. With the 90 sheet metal the members G may be flanged by a simple die, comprising male and female die portions, with guides provided at the sides of the female die to insure proper alignment of the angles of the vertical and 95 oblique flanges, characterizing devices of this character. With this construction the conventional underframe may be used, comprising cross-bearers and bolsters, with either single or double center sills, and the 100 pressings or castings G may be placed in position above the bolster cover plate I, resting on the horizontal flanges B of the bolster, and secured thereto by vertically disposed rivets B', and secured to the vertical end flanges of the bolster by horizontally 105

disposed rivets S, which rivets also extend through the outstanding flanges of the side post 2.

By using metal pressings G with vertical flanges 3 and oblique flanges 4, a rigid connection is provided between the side sheets of the car body and the bolster, which is of much greater strength than would be practicable if this connection were formed by a horizontal extension of the side sheet. It is evident that a relatively narrow plate, such as will be required to form the member G, can be pressed to form with less trouble and expense than if the entire side sheet of the car is bent to the form of the plate G, and it is also evident that it would be commercially unprofitable to form side sheets of the car of a thickness of metal which is found necessary for use in constructing the member G.

An additional feature of advantage in the angular member G is that it may be utilized as a support for door operating elements commonly employed to lift or to lift and lock the drop doors usually carried by cars of this construction. When the member G, or some modification of the same, is used to support the door actuating members, it is usually supported directly from the transverse members of the underframe.

With link and crank arm devices used for lifting such doors, it is preferred that the member G shall be relatively narrow transversely of the car, and may be offset outwardly at intervals along its oblique inner flange to provide a clearance between such flange and the inclined lower end of the side plate for passage therethrough of the door lifting means.

Where winding shaft and chain lift is employed, as in Figs. 3 and 6, the member G may be perforated at intervals, as shown at 10, in Fig. 7 for the passage therethrough of a winding chain adapted to wind on the shaft 8, shown in Figs. 3 and 6, although it is to be understood that a similar shaft may be supported above any of the modified forms of plates herein disclosed. When the chain is used the plate G is preferably wider, and may be provided with a corrugation embracing the shaft 8, a corrugation 9, acting as a shoulder, against which the shedding surface rests and the oblique overlapping flange 4 fastened by means of rivet 12 to the lower end of the sheet H.

It is further noticed that the oblique flange 4 of the member G may be extended to provide space for one or more rows of rivets connecting it to the inwardly disposed lower portion of the side sheet H, or its flange 6 may be formed, as shown in Fig. 3, outside of the shedding surface H, the shedding surface being extended downwardly to bear within the angle, as shown in Fig. 4.

The flange 4 may be positioned beneath the

oblique portion of the sheeting H, and the angular plate 15 may have one portion disposed beneath the member G and disposed between the member G and the bolster F, and have an inclined portion 16 overlapping the lower edge of the sheeting H and the flange 6. By these constructions it is noted that the member G is of greater thickness than the side sheeting, forming in effect a side sill having a vertical flange and an oblique flange, and with a separate web portion horizontally disposed for the greater portion of its width.

While the member G has been referred to as a side sill or sheeting, it is, of course, to be understood that the side of the car disclosed is a plate girder preferably provided with the usual compression flanges at the top, but, if desired, the member G may be utilized as a side sill formed as a truss and lined by metal sheeting, as is common in the old wood car.

As shown in Figs. 3 and 6, the door I' with its reinforcing angle A may be used and the inner angle of the member G will serve as a stop to limit upward or closing movement of the door I' which latter is shown in fragmentary detail only as no claim is made to the door.

What I claim is:

1. In a dumping car the combination comprising a plurality of transverse underframe members; a Z-shaped side sill of relatively thick metal connecting said members, said sill having an oblique flange, posts connected with some of said transverse members, and a sheet metal side wall terminating above said transverse members and of less thickness than said sill and said side wall lapping said oblique flange and being connected respectively with said posts and oblique flange.

2. In a car construction, transverse members, a vertical side wall provided with inwardly bent lower portion terminating above said transverse members, side posts, and a relatively Z-shaped member with a horizontal web portion between said wall and transverse members, connecting a plurality of said transverse members and having an inclined flange connected to the lower portion of the side wall.

3. In a car construction, a plurality of transverse members, a side wall, a part of which is in relative vertical alignment with the ends of some of said members and which is provided with an oblique lower end portion terminating above said transverse members, a side sill having a horizontal web and oblique flange resting on the transverse members and connecting a plurality of the transverse members and connected directly to said oblique lower end of the side wall.

4. In a car constructed with sheet metal side walls having a vertical portion and an

- inwardly inclined lower portion terminating above the cross-bearers, cross-bearers, a flanged plate of metal thicker than the metal of the side walls and having a horizontal 5 web portion secured to and connecting a plurality of said cross-bearers having an oblique flange lapping and being connected to said inwardly inclined wall portion whereby the load shedding portion of the 10 wall is reinforced and connected with said cross-bearers.
5. In a car constructed with sheet metal side walls having an inwardly inclined load shedding portion, an underframe comprising a plurality of transverse members, a relatively Z-shaped member with horizontal web and inclined flange extending parallel 15 with the inclined portion of said wall and connected thereto, the horizontal web of said 20 Z member being connected with the top and ends of a plurality of said transverse members.
6. In a dumping car, the combination comprising a cross-bearer, a side wall extending over a portion of the cross-bearer, a 25 plate connected with said wall and cross-bearer and a door lifting shaft resting on said plate.
7. A car wall comprising a relatively 30 large thin sheet having its lower side bent inwardly to form a shedding surface and a separate relatively heavy connecting plate of substantially Z-shape in cross section lap-
- ping and being fastened thereto and constituting the lower portion of said shedding 35 surface.
8. In a car, a side wall vertical for a portion of its depth and oblique for another portion, transverse underframe members, posts connected with said wall and members, 40 a Z-shaped plate lapping the oblique portion of said wall and connecting said transverse underframe members, and a shaft above said members between the posts and said wall. 45
9. In a car, a wall comprising a sheet of metal vertical for a portion of its depth and inclined inwardly of the car near its bottom, a plurality of posts connected to said vertical portion, a Z-shaped plate connecting said sheet with all of said posts, and a winding shaft between said post and the inclined portion of said wall. 50
10. In a dumping-car, the combination comprising a plurality of cross-bearers, a Z- 55 shaped side sill connecting said cross-bearers, a door operating shaft supported above said side sill and a dumping door underlapping said sill when said door is in closed position. 60

In witness whereof I have hereunto set my hand in the presence of two witnesses.
